UNITED STATES PATENT OFFICE.

ARTHUR M. BARRETT, OF CHICAGO, ILLINOIS.

TRUCK.

1,125,634.

Specification of Letters Patent. Patented Jan. 19, 1915.

Application filed March 26, 1914. Serial No. 827,305.

To all whom it may concern:

Be it known that I, ARTHUR M. BARRETT, a citizen of the United States, residing at Chicago, in the county of Cook, in the 5 State of Illinois, have invented certain new and useful Improvements in Trucks, of which the following is a specification, reference being had to the accompanying drawings.

10 This invention relates to trucks and particularly to that class of truck adapted to be used with a removable platform which may be lifted and carried by the truck. In commercial use, a single truck is often provided for use with a great number of platforms under any one of which the truck is adapted to be run for lifting the platform and carrying it to the desired point.

It is one of the objects of my invention 20 to provide a new and improved construction and arrangement of lifting mechanism by reason of which an operator is enabled to lift a greater load than with the prior constructions.

25 It is another object of my invention to provide an arrangement and construction of lifting devices in which the stroke of the lifting lever is effective for the lifting operation through a greater angle than has heretofore been attained, thus making possible the lifting of increased loads.

It is another object of my invention to 30 secure increased leverage over prior constructions by reason of providing shorter lifting levers at the front between the side bars of the truck than are used at the rear ends thereof.

It is another object of my invention to 35 provide for moving the rear supporting 40 wheels of the truck forward as the load is raised upon them, thus increasing the distance which the upper ends of the rear lifting levers must move during the raising operation and to that extent increasing the 45 effective leverage.

It is another object of my invention to 50 provide a new and improved form and arrangement of truck for use with pianos, or similar heavy articles, by which the piano

through the medium of special lifting devices and without the use of a platform.

It is another object of my invention to provide a two-wheeled elevating truck or dolly for use at one end of a beam or device 55 which is too long for convenient handling upon a short truck.

It is another object of my invention to improve devices of this general type in sundry details hereinafter pointed out.

The preferred means by which I have accomplished these objects are illustrated in the accompanying drawings and are herein-after specifically described.

That which I believe to be new and 60 65 which I wish to cover by this application is set forth in the claims.

In the drawings:—Figure 1 is a side view of my improved truck with the side bars locked in raised position, the tongue or handle being broken away; Fig. 2 is a similar view but with the side bars in one of their two lowered positions; Fig. 3 is a side view of my improved truck in position under a platform with the side bars in their 70 75 lowermost position; Fig. 4 is a front view of my improved truck with the side bars in raised position; Fig. 5 is a central vertical section through the front end of the truck, being taken substantially on line 5—5 of 80 Fig. 4; Fig. 6 is substantially a vertical section taken on line 6—6 of Fig. 4; Fig. 7 is a view showing a modification of the form of truck shown in the figures heretofore described, being specially adapted for use 85 with pianos; Fig. 8 is a cross-section taken on line 8—8 of Fig. 7; Fig. 9 is a view showing the use of two two-wheeled elevating trucks or dollies for moving a long beam; Fig. 10 is an enlarged detail of one 90 of the trucks shown in Fig. 9; showing the same in lowered position; and Fig. 11 is a front view of one of the dollies shown in Fig. 9, with the same shown in raised position.

95 Referring now to Figs. 1 to 6, inclusive, in which corresponding parts are indicated by the same reference characters:—20 indicates a front axle member comprising an axle 21 and a king-bolt 22, the body of the 100

axle member being cast about said axle and said king-bolt for securing them in proper position. The axle member 20 has projecting from its front side two lugs 23-24 between which a tongue or handle 25 is pivotally mounted by means of a pin 26. As best shown in Fig. 5, the rear end of the handle 25 is adapted to bear against a shoulder 27 of the axle member 20 so as to limit the movement of the handle in clockwise direction relative to said axle member. The axle 21 has mounted upon its outer ends carrying wheels 28-29 of any suitable construction. 30 indicates a bolster mounted upon the king-bolt 22 and adapted to turn thereon relative to the axle member 20, said bolster comprising downwardly-extending arms 31-32 at its ends. Pivotally mounted upon the bolster 30 is a U-shaped cross-head 33, the lower ends of the arms of which are pivotally mounted upon studs 34-35 extending outwardly from the arms 31-32 of the bolster 30. Upon said studs 34-35 are mounted also near their forward ends main side bars 36-37, respectively. Each of said side bars is turned upward at its forward end to afford an offset mounting for said bar, the bar 37 being extended upward to provide a standard 38. The rear ends of the side bars 36-37 are pivotally mounted upon an axle 39 carrying supporting wheels 40 journaled thereon in any suitable manner. 41-42 indicate the lifting links or bars of the truck mounted at their forward ends by means of pins 43-44, respectively, upon the arms of the cross-head 33 a short distance from the pins 34-35. Said bars 41-42 are mounted at their rear ends by means of a rod 45 extending through the upper ends of arms 46 mounted at their lower ends upon said rear axle 39.

Referring now particularly to Figs. 4 and 5, 47-48 indicate lugs rising from the bolster 30 at about its central point, pivoted between which, upon a pin 49, is a latch-lever 50. Said lever 50 is provided with a tooth 51 upon its upper face adapted to engage a suitable recess in the under face of the cross-head 33 so as to hold said cross-head against movement in counterclockwise direction in Fig. 5 relative to said bolster. The lever 50 is held against swinging too far upward relative to the bolster 30 by reason of its end portion coming in contact with the body of the bolster. Said lever is held normally in latching position as shown in Fig. 5 through the medium of a coiled spring 52 interposed between the lever and the bolster. 53 indicates a lug rising from the bolster 30 near one end thereof having pivotally mounted thereon by means of a pin 54 a latch-lever 55. Said lever 55 is provided at its forward end with a notch 56 adapted to engage a pin 57 carried near the

upper end of the standard 38. As best shown in Fig. 6, the latch-lever 55 is kept from turning too far in clockwise direction relative to the bolster 30 by means of a pin 58. A coiled spring 59 interposed between the rear end of the lever 55 and the bolster 30 holds the lever 55 normally in latching position as will be readily understood. The lever 55 carries at its rear end an arm 60 by the use of which the operator is enabled to release the lever by pressing thereon with the foot. 61 indicates a cross-bar secured between the lifting bars 41-42. In the construction shown this cross-bar is in the form of an angle-bar, being secured to the bars 41-42 by the turned ends of one side 80 thereof.

With the parts in the condition shown in Fig. 2 the truck is adapted to be backed under a suitable platform, as 62, until the stop 61 is brought into contact with the edge 85 of the platform. The operator can then readily release the latch-lever 55 from the pin 57 with his foot, permitting the bolster and the axle member to turn into the position shown in Fig. 3. As the bolster 30 reaches its lowermost position, the tooth 51 carried by the latch-lever 50 is caused to enter the recess in the cross-head 33, effectively locking said bolster and said cross-head together, with the arms of the cross-head in engagement with the pins 63 of the bolster. A stroke of the handle or lever 25 in clockwise direction, in the figures thereupon causes the bolster and cross-head to revolve in clockwise direction, bringing the pivot pins 34-35 and the side bars 36-37 forward and upward relative to the front axle 21, and moving the lifting bars 41-42 also forward and upward. As the stroke of the lever 25 continues, the side-bars 36-37 cause the supporting wheels 40 to be drawn gradually forward relative to the front supporting wheels 28-29. At the same time the lifting bars 41-42 are drawn more rapidly forward, causing the bars 41-42 to move forward relative to the bars 36-37, bringing the parts finally into the position shown in Fig. 1. As this movement is being completed, the latch-lever 55 is caused to engage the pin 57, locking the parts in the position shown in said Fig. 1. As will be readily understood, by reason of the forward movement of the axle 39 relative to the bolster 30 and the cross-head 33, actuated through the medium of the side bars 36-37 as above described, upon an operative stroke of the lever or handle 25, the angle through which the said lever 25 moves is greater than that through which the arms 46 move in the same period of time, whereby a material gain in the effective leverage of the mechanism is attained. After the parts have been brought to the position shown in Fig.

1, but with a loaded platform in position on the lifting bars 41-42, the truck can be drawn to any desired point, the handle 25 being free to be swung up and down as desired and the front axle 21 being free to be angled horizontally as desired relative to the platform. When the platform has been brought to the desired position upon the floor, the latch-lever 55 can be released by the foot of the operator and the platform with its load can then through the medium of the handle 25 be lowered gradually into position upon the floor, the parts assuming the position shown in Fig. 3. The latch-lever 50 may then be released if desired and the bolster 30 may be raised through the medium of the handle 25 until the latch-lever 55 again engages the pin 57, bringing the truck into the condition shown in Fig. 2. The handle 25 can then be raised and lowered freely and the axle 21 can also be angled for controlling the direction of movement of the truck. If desired, when the truck is locked in the position shown in Fig. 1, but with a loaded platform thereupon, the lever 50 may be released, permitting the lifting bars 41-42 to drop immediately to the position shown in Fig. 2. It will be noted that the distance between the pivots 34 and 43 is less than the distance between the pivot 39 and the rod 45; consequently, as the arms 31-32 act as levers to pull the lifting bars 41-42 forward and so rock the arms 46 to lift the rear ends of the lifting bars, I obtain greater leverage and increased lifting effect with a given expenditure of power. Owing to this arrangement and to the inclination forward and downward of the lifting bars, the rear ends of the lifting bars become operative to lift the load before the front end portions of said bars do any lifting, and therefore as only part of the load is lifted at first, the work of raising the entire load is made much easier.

In Figs. 7 and 8, in which I have shown a modified form of construction for use especially with pianos or similar heavy articles, corresponding parts are indicated by the same reference characters, but with the addition of the exponent *a*. In this construction the main side-bars which are in the form of angle-bars are indicated by the numerals 64-65. As shown in Fig. 7, the side-bars 64-65 are connected near their forward ends by a bracket 66 by which said bars are strengthened against lateral movement relative to each other. Each of the side bars 64-65 has journaled in it an axle 67 carrying supporting wheels 68-69. Upon each side of each of said side-bars 64-65 there is a link 70 pivotally mounted at its lower end upon the axle 67, said links 70 being connected at their upper ends to the

lifting bars 41^a-42^a, respectively, by means of pins 71-72.

As will be readily understood, the operation of the truck as illustrated in Figs. 7 and 8 is the same as that of the truck heretofore described. In practice, a plurality of U-shaped brackets 73 will be provided having outwardly extending arms at their upper ends adapted to be engaged by the lifting bars of the truck. A piano or other similar heavy article, which it is desired to have moved frequently about a factory, either in the course of manufacture or at any other time, will be provided with two or more of such U-shaped brackets 73. A truck of the type just described can then be backed under the horizontally-extending arms of the U-shaped brackets with the side bars of the truck on opposite sides of the piano and the piano can be lifted in the manner heretofore described. If desired, a platform having outwardly-extending arms can be used in lieu of the brackets.

Referring now to Figs. 9, 10 and 11 which show the construction of my improved dolly, 74 indicates an axle member provided with an axle 75 and a suitable king-bolt, not shown, the member 74 being cast directly about said axle and said king-bolt. The axle 75 has mounted upon its ends carrying wheels 76-77. The axle member has mounted upon it so as to turn upon a king-bolt carried thereby a bolster 78 comprising arms 79-80 extending downwardly at its ends. The bolster 78 has pivotally mounted upon it a cross-head 81 comprising arms 82-83 by which it is pivotally connected with the bolster 78 upon the pins 84-85 respectively. As best shown in Fig. 10, the cross-head 81 has a flat upper face with the exception of a stop 86 secured thereon. 87 indicates a stop carried by the arm 83 of the cross-head adapted to contact a stop 88 mounted upon the bolster for limiting the movement of such parts relative to each other upon the pins 84-85, as is shown in Fig. 10. For locking the bolster and cross-head together to prevent relative movement a latch-lever 89 is provided, mounted upon the arm 82 of the cross-head 81 by means of a pin 90. As best shown in said Fig. 10, said latch-lever is provided near its end with a notch 91 adapted to engage a pin 92 carried by the bolster 78. The latch-lever 89 is held against movement too far in clockwise direction in said Fig. 10 by means of a pin 93 carried by the arm 82 of the cross-head. The latch-lever is held normally in position to engage the pin 92 by means of a coiled spring 94 interposed between the upper face of said lever and the under face of the cross-head. The axle member 74 is provided with two lugs 95-96 between which, by means of a pin 97, a handle or lever 98 is mounted. As

shown in Fig. 10, the lower end of the handle 98 is adapted to be inserted into a socket 99 formed in the axle member 74, the opening in the handle 98 through which the pin 97 extends being in the form of a slot 100 in order to permit of the longitudinal movement of said handle.

With the parts of my improved dolly in the position shown in Fig. 10, the dolly is adapted to be run under one end of a beam or other part 101, supported by horses 102 or in any other suitable manner, the cross-head 81 being run directly under the end of the beam up to the point where the beam comes in contact with the stop 86. The handle or lever 98 is then given a movement in counterclockwise direction in Fig. 10 thus turning the axle member 74 and with it the bolster 78, causing the cross-head 81 to rise into contact with the beam 101 and raising said beam by the further upward movement of the cross-head. As the bolster 78 comes substantially into vertical position above the axle 75 which will have moved to the right in Fig. 10 during the raising operation, the latch-lever 89 will be brought into operative engagement with the pin 92 thus locking the cross-head and the bolster together, with the handle 98 standing in oblique position as is shown at the right in Fig. 9. With the handle in this position, the axle 75 is free to turn upon the king-bolt, as will be readily understood. With a dolly in position at each end of the beam 101 and with the cross-heads of the dollies locked in elevated position, the beam can be moved as desired by the use of one of the handles 98. It is preferable, however, that the axle 75 of the dolly which is in the rear in the movement of the beam should be locked against swinging horizontally relative to the cross-head. This can be accomplished by moving such handle upward longitudinally of itself to free the lower end of the handle from the socket 99. The handle may then be turned into vertical position, as shown at the left in Fig. 9, into position in a notch 103 in the edge of the cross-head whereby the handle and the axle are held against swinging upon the king-bolt, as will be readily understood. The handle when moved in vertical position in this way is adapted to be retained in such position by being slid downward in contact with a shoulder 104 of the axle member, best shown in Fig. 10. It will be readily understood that by reason of the engagement of the flat upper face of the dolly with the under face of the beam the dolly as a whole is held against tipping on a transverse axis, inasmuch as such tipping would involve a preliminary raising of that end of the beam.

While I have shown the use of two similar dollies at the ends of the beam it will be understood that I do not wish to limit my-

self to the use of similar devices. As will be readily seen, with a beam supported on two such dollies as shown in Fig. 9, when both handles 98 are turned laterally toward the same side, the beam is free to fall toward the opposite side. I therefore contemplate the use of a dolly such as that shown at one end, while at the other end of the beam a dolly is used of somewhat similar construction but not involving the pivotal connection between the axle and the beam-supporting plate.

So far as I am aware, I am the first in the art to provide shorter links or levers for connecting the front ends of the lifting bars with the front ends of the side-bars than are used at their rear ends, by the use of which short centers in front increased leverage is attained, and I desire accordingly to claim this feature broadly, both in the particular embodiment illustrated by the drawings and in any other similar or equivalent constructions. By reason of my arrangement and construction, in which the front end of the links or bars 41 when in lowered position are lower than the rear ends of said bars, the rear ends of the said lifting bars 41 are brought into contact with the platform 62 earlier than are the front ends and consequently begin their effective lifting operation sooner. The arrangement is such that the arms 46 are very nearly in a vertical position with the rear ends of the bars 41 very nearly in their uppermost position before the front ends of the said bars begin their lifting operation. This results in a much greater effectiveness for lifting heavy loads than would be attained if both ends of the said bars performed the heaviest part of their lifting at the same time.

As will be appreciated upon an inspection of the drawings, the cross-head 33, the bolster 30, the axle-member 20, and the handle 25, when latched together as in Fig. 3, constitute in effect a single lever adapted to turn about the axle 21 as an axis.

What I claim as my invention and desire to secure by Letters Patent is,

1. In an elevating truck, the combination with a carriage comprising front and rear wheels, side-bars connected with the rear wheels, and a lever fulcrumed upon the axis of the front wheels and having a member by which it is connected with the front end portions of said side-bars eccentrically relative to said axis, of lifting bars, and arms connecting the rear end portions of said lifting bars with the carriage, said lever being also connected with the front end portions of said lifting bars.

2. In an elevating truck, the combination with a carriage comprising front and rear wheels, side-bars connected with the rear wheels, and a lever fulcrumed upon the axis of the front wheels and connected with the

front end portions of said side-bars, of lifting bars, arms pivotally connected with the rear end portions of said lifting bars, and connections between said lever and the front end portions of said lifting bars, the front and rear wheels being adapted to be moved slightly closer together by the operative lifting stroke of said lever.

3. In an elevating truck, the combination of a side-bar, a supporting wheel revolvably mounted on said side-bar, an arm pivotally mounted on the axis of said supporting wheel, a lifting bar pivotally connected to said arm, a lever pivotally connected to both of said bars, and a supporting wheel about which the pivotal connection between said lever and said side-bar is adapted to be moved by a stroke of said lever.

4. In an elevating truck, the combination of a side-bar, a supporting wheel revolvably mounted on said side-bar, an arm pivotally mounted on the axis of said supporting wheel, a lifting bar pivotally connected to said arm, a lever pivotally connected to both of said bars, and a supporting wheel about which the pivotal connection between said lever and said side-bar is adapted to be moved by a stroke of said lever, the distance between the pivotal connections of said lever to said bars being shorter than the distance between the pivotal connections of said arm to said bars.

5. In an elevating truck, the combination of a side-bar, an arm pivotally mounted thereon, a lifting bar pivotally connected to said arm, and a lever pivotally connected to both of said bars eccentrically relative to the axis upon which said lever turns for moving both of said bars longitudinally of themselves, whereby upon a stroke of said lever said arm is swung about its pivotal connection with said side-bar and at the same time the axis about which the arm is swinging is moved in the same direction.

45 6. In an elevating truck, the combination of a side-bar, an arm pivotally mounted thereon, a supporting wheel revolvably mounted on the pivotal axis of said arm relative to said side-bar, a lifting bar pivotally connected to said arm, a lever pivotally connected to both of said bars eccentrically relative to the axis upon which said lever turns for moving both of said bars longitudinally of themselves, and a supporting wheel mounted upon said axis relative to which supporting wheels said lever turns, a stroke of said lever serving to swing said arm about its pivotal connection with said side-bar and at the same time to move in the same direction the axis about which said arm swings.

7. In an elevating truck, the combination with a carriage comprising side-bars and front and rear wheels connected with the end portions of said side-bars, of lifting bars,

and swinging members pivotally connecting the front and rear end portions of said lifting bars respectively with said side-bars, the connections of the front end portions of said side and lifting bars being closer together 70 than the connections of the rear end portions thereof.

8. In an elevating truck, the combination with a carriage comprising side-bars and front and rear wheels connected with the end 75 portions of said side-bars, of lifting bars, swinging members pivotally connecting the front and rear end portions of said lifting bars respectively with said side-bars, the connections of the front end portions of said 80 side and lifting bars being closer together than the connections of the rear end portions thereof, and a lever for swinging the front connections.

9. In an elevating truck, the combination 85 with a carriage comprising side-bars and front and rear wheels connected with the end portions of said side-bars, of lifting bars, arms pivoted upon the carriage and pivotally connected to the rear end portions of 90 said lifting bars, and levers pivotally connected to the front end portions of said side bars and said lifting bars, the pivots of the front end portions of said side bars and said lifting bars being closer together than the 95 pivots of the rear end portions thereof.

10. In an elevating truck, the combination with a carriage comprising side-bars and front and rear wheels connected with the end 100 portions of said side-bars, of lifting bars supported by the carriage, and mechanism for raising the lifting bars, said mechanism operating automatically to start raising said lifting bars at one end before they are raised at the other end.

11. In an elevating truck, the combination of a longitudinally-extending bar, an arm adapted to swing about an axis movable with said bar, a cross-head adapted to be swung about a horizontal axis, means for connecting said arm and said cross-head whereby an operative stroke of said cross-head causes a stroke of said arm for lifting purposes, and means for pivotally connecting said bar to said cross-head between the point of connection of said first-named connecting means to said cross-head and the axis of revolution of said cross-head.

12. In an elevating truck, the combination of a longitudinally-extending bar, an arm adapted to swing about an axis movable with said bar, a lever adapted to swing about a horizontal axis, a second bar connecting said arm and said lever adapted to be raised by an operative stroke of the lever, and means for connecting said first-named bar to said lever between the point of connection of said second bar to said lever and the axis of revolution of said lever.

13. In an elevating truck, the combination 130

of a longitudinally-extending bar, an arm adapted to swing about an axis movable with said bar, a cross-head adapted to swing about a horizontal axis, a second bar connecting said arm and said cross-head adapted to be raised by an operative stroke thereof, and means for connecting said first-named bar to said cross-head between the point of connection of said second bar there-

10 to and the axis of revolution thereof.

14. In an elevating truck, the combination of a longitudinally-extending bar, an arm adapted to swing about an axis movable with said bar, a cross-head adapted to be swung about a horizontal axis, a second bar directly over said first-named bar connecting said arm and said cross-head and adapted to be raised by an operative stroke thereof, and means for connecting said first-named bar to said cross-head between the point of connection of said second bar thereto and the axis of revolution thereof, said first-named bar being offset at its forward end whereby said cross-head is adapted to turn into substantially horizontal position.

15. In an elevating truck, the combination of a longitudinally-extending bar offset vertically at one end, a second bar, an arm pivotally connecting said bars at their straight ends, a lever pivotally connecting said second bar with the offset portion of said first-named bar, and means for swinging said lever for raising one of said bars relative to the other bar.

35 16. In an elevating truck, the combination of a longitudinally-extending bar offset upward at one end, a second bar, an arm pivotally connecting said bars at their rear ends whereby the upper bar is adapted to rest upon said first-named bar or to be raised out of contact therewith, a lever pivotally connecting said second bar with the offset portion of said first-named bar, the pivots of said lever being closer together than the pivots of said arm, and means for swinging said lever for raising the upper bar out of contact with the first-named bar.

17. In an elevating truck, the combination of two longitudinally-extending bars one at 50 each side of the truck each offset upward at one end, two other bars, arms pivotally connecting said bars at their straight ends whereby the upper bars are adapted to rest upon said first-named bars or to be raised out of contact therewith, a cross-head the ends of which serve to pivotally connect said second-named bars with the offset portions of said first-named bars, and means for swinging said cross-head for raising said 60 second-named bars.

18. In an elevating truck, the combination of a longitudinally-extending bar, a lifting lever pivotally mounted relative to said bar, an arm pivotally mounted relative to said bar, and a link pivotally connecting said

lever with said arm, the distance between the axis of rotation of said lever and the connection of said link thereto being less than the distance between the axis of rotation of said arm and the connection of said link thereto.

19. In an elevating truck, the combination of a longitudinally-extending bar, an arm adapted to have an operative stroke from a diagonal position to approximately a vertical position, a lever pivotally mounted relative to said bar, a link pivotally connecting said arm with said lever, the distance between the axis of rotation of said lever and the connection of said link thereto being less than the distance between the axis of rotation of said arm and the connection of said link thereto, and means for moving said lever through an angle of approximately ninety degrees relative to said bar for an operative stroke of said arm through a smaller angle.

20. In an elevating truck, the combination of a longitudinally-extending bar, a lifting lever pivotally mounted relative to said bar, an arm pivotally mounted relative to said bar, a link pivotally connecting said arm with said lever, and means for turning said lever about an axis located eccentrically relative to the connection between said lever and said bar whereby said link and said bar are moved longitudinally.

21. In an elevating truck, the combination of a longitudinally-extending bar, a lifting lever pivotally mounted relative to said bar, an arm pivotally mounted relative to said bar, a link pivotally connecting said arm with said lever, the distance between the pivotal connection of said lever with said bar and the connection of said lever with said link being less than the distance between the axis of rotation of said arm and the connection of said link thereto, and means for turning said lever about an axis located eccentrically relative to the connection between said lever and said bar, the distance between said axis and the point of connection of said link with said lever being approximately the same as that between the axis of rotation of said arm and the connection of said link thereto.

100 22. In an elevating truck, the combination of a frame, a bolster pivotally connected with said frame, said bolster being adapted to be tilted on an axis below the axis on which it turns relative to the frame, a cross-head pivotally mounted on said last-mentioned axis, lifting bars connected with said cross-head, and means for locking said cross-head and said bolster together.

110 23. In an elevating truck, the combination of a frame, a bolster pivotally connected with said frame, said bolster being adapted to be tilted on an axis below the axis on which it turns relative to the frame, a cross-head pivotally mounted on said last-men-

tioned axis, lifting bars connected with said cross-head, means for locking said cross-head and said bolster together, and means for locking said bolster against turning relative to said frame.

24. In an elevating truck, the combination of a pair of oppositely-disposed side bars offset upward at their forward ends, a bolster pivotally mounted between the offset portions of said side bars, said bolster being adapted to be tilted on an axis below the axis upon which it turns relative to said bars, a cross-head pivotally mounted on the offset portions of said side bars, arms pivotally connected to said side bars at their rear ends, lifting bars pivotally connected at their rear ends to said arms and at their front ends to said cross-head, means for locking said cross-head and said bolster together, and means for tilting said bolster.

25. In an elevating truck, the combination of a pair of oppositely-disposed side bars offset upward at their forward ends, a bolster pivotally mounted between the offset portions of said side bars, an axle member pivotally connected with said bolster and adapted to be swung on a vertical axis relative thereto, carrying wheels mounted on said axle member on an axis below the pivotal connection between said bolster and said side bars, a cross-head pivotally mounted on the offset portions of said side bars, arms pivotally connected to said side bars at their rear ends, lifting bars pivotally connected at their rear ends to said arms and at their front ends to said cross-head, means for locking said cross-head and said bolster together, and means for tilting said bolster.

26. The combination of an axle member in the form of a casting about an axle and a king-bolt, carrying wheels mounted on said axle, a bolster pivotally mounted on said king-bolt, a cross-head pivotally mounted on said bolster above the axis of said carrying wheels thereon, and means for tilting said bolster upon said carrying wheels for raising and lowering said cross-head.

27. In an elevating-truck, the combination of an axle-member, a bolster revolvably mounted on said axle-member, a frame pivotally connected with said bolster whereby said bolster and said axle-member are adapted to be tipped relative to said frame, elevating means movably mounted relative to said frame adapted to be actuated for raising a load relative to said frame, means for locking said elevating means to said bolster for operation thereby, and independently-operable means for locking said bolster against movement relative to said frame.

28. In an elevating-truck, the combination of an axle-member, a bolster revolvably mounted on said axle-member, a frame pivotally connected with said bolster whereby said bolster and said axle-member are adapt-

ed to be tipped backward relative to said frame, elevating means movably mounted relative to said frame adapted to be actuated by the movement of said bolster into vertical position for raising a load relative to said frame, means for locking said elevating means to said bolster for an operative stroke thereby for raising a load, and independently-operable means for locking said bolster against movement relative to said frame.

29. In an elevating truck, the combination of an axle-member, a bolster revolvably mounted on said axle-member, a frame pivotally connected with said bolster whereby said bolster and said axle-member are adapted to be tipped relative to said frame, a cross-head pivotally mounted relative to said bolster, means actuated by a stroke of said cross-head in one direction for raising a load relative to said frame, means for locking said cross-head to said bolster for operation thereby as said bolster is moved to normal vertical position, and independently-operable means for locking said bolster against movement relative to said frame.

30. In an elevating-truck, the combination of an axle-member, a bolster revolvably mounted on said axle-member, a frame pivotally connected with said bolster whereby said bolster and said axle-member are adapted to be tipped relative to said frame, a cross-head pivotally mounted relative to said bolster, means actuated by a stroke of said cross-head in one direction for raising a load relative to said frame, means for locking said cross-head to said bolster for operation thereby as said bolster is moved to normal vertical position, and independently-operable means for locking said bolster against movement relative to said frame, said load being adapted to be lowered relative to said frame either by the tilting of said bolster upon the release of said second-named locking means or by the movement of said cross-head independently of the bolster upon the releasing of said first-named locking means.

31. In an elevating-truck, the combination of an axle-member, a bolster revolvably mounted on said axle-member, a frame pivotally connected with said bolster whereby said bolster and said axle-member are adapted to be tipped relative to said frame, elevating means movably mounted relative to said frame adapted to be actuated by said bolster as it is moved to normal vertical position for raising a load relative to said frame, and a latch-lever for locking said bolster against movement relative to said frame, said latch-lever being adapted to be released by a downward and backward pressure by the foot of the operator.

32. In an elevating-truck, the combination of an axle-member, a bolster revolvably mounted on said axle-member, a frame pivotally connected with said bolster whereby

said bolster and said axle-member are adapted to be tipped relative to said frame, elevating means movably mounted relative to said frame adapted to be actuated by said bolster as it is moved to normal vertical position for raising a load relative to said frame, and a latch-lever pivotally mounted on said bolster for locking said bolster against movement relative to said frame,

10
said latch-lever being adapted to be released and said bolster being adapted to be given a backward thrust by a downward and backward pressure upon the latch-lever by the foot of the operator.

ARTHUR M. BARRETT.
